GEOMETRICAL INSTRUMENT

Daniel J. McQuaid, Sr., Denver, Colo.

Application August 10, 1945, Serial No. 610,013

6 Claims. (Cl. 33—104)

1

This invention relates to geometrical instruments, and the present application is a continuation-in-part of my co-pending application Serial No. 422,201, filed December 9, 1941, which is a continuation of my application Serial No. 283,525, filed June 10, 1939.

Among the objects of this invention are to provide a novel geometrical instrument or device which is useful in making mechanical drawings; to provide such a geometrical instrument which is particularly useful in making dimetric drawings and projections; to provide such an instrument which is particularly useful in making optically balanced axonometric drawings and projections; to provide such an instrument which is particularly useful in making axonometric drawings and projections of objects and the like in which lines or the like extend at different angles, such as 45°, to the normal principal axes; to provide such an instrument which is particularly useful in making drawings of piping systems of houses, apartments, factories and the like; to provide different forms of such instruments to increase the utility thereof; and to provide such an instrument which is simple in construction and relatively inexpensive to manufacture. Other objects and novel features of this invention will become apparent from the description which follows.

In general, a geometrical drawing instrument may be constructed in accordance with this invention so as to be provided with a plurality of co-planar edges, either interior or exterior, or both, one of the edges being a base edge, and the other edge being inclined thereto at certain specified angles. Thus, at least one edge is inclined to the base edge at an angle of 36° 52' 11.63", one or more edges may be inclined to the base edge at an angle of 10° 37' and 10", and one or more additional edges may be inclined to the base edge at an angle of 59° 21' 00". Other details, and different embodiments of this invention are illustrated in the accompanying drawings, in which

Fig. 1 is a plan view of one embodiment of the invention;

Fig. 2 is a plan view of the second embodiment of this invention; and

Fig. 3 is a piping diagram illustrating one use of the instruments of this invention.

The embodiments of this invention illustrated in Figs. 1 and 2 comprise instruments or devices D and D', each of which is provided with a base edge 10 and exterior edges 11 and 11', 12 and 12' which are co-planar with base edge 10 and inclined at an angle of 36° 52' 11.63" thereto, but

5 extend generally in opposite directions. In device D of Fig. 1, edges 10, 11 and 12 comprise all the exterior edges, while device D' of Fig. 2 has, in addition to edges 10, 11' and 12', exterior edges 13 which are disposed at an angle of 90° to base edge 10. The edges 11 and 12 of device D intersect at a common upper point, as shown, as do also the edges 11' and 12' of device D' at a common lower point. Edges 11 and 12 of device D also intersect base edge 10 at spaced lower points as shown, while the edges 11' and 12' of device D' intersect edges 13 at upper spaced points. Thus, the edge 11 of device D and edge 11' of device D' extend in the same direction with respect to the base edge, but are on opposite sides of the device, and the same relationship exists in the case of edges 12 and 12' of the two devices.

20 Device D is also provided with apertures 20, 30 and 40 which provide additional but interior edges, and device D' is similarly provided with apertures 20' and 30' which are similar to apertures 20 and 30, respectively, though larger, but are disposed on opposite sides of the device. 25 Aperture 20 provides two interior edges 21 and 22, edge 21 being inclined at an angle of 10° 37' 10" to base 10, while edge 22 is inclined at an angle of 59° 21' to base edge 10. Similarly, aperture 30 provides an interior edge 31 which is inclined at an angle of 10° 37' 10" to base edge 10 but extends in the opposite direction to edge 21 of aperture 20, and an interior edge 32 which is inclined at an angle of 59° 21' to base edge 10 but extends in the opposite direction to edge 22 of aperture 20.

30 Apertures 20 and 30 are preferably triangular in shape, the third edge 23 and 33, respectively, of each aperture being parallel to the adjacent exterior edge 11 and 12, respectively, of each aperture being parallel to the adjacent exterior edge 11 and 12, respectively, not only for convenience in manufacture, but also as indicative of the use of the other edges 21 and 22 of aperture 20 and 31 and 32 of aperture 30. 35 In this connection, it is to be noted that the edges 22 and 32, respectively, of apertures 20 and 30, which are inclined at the greater angle to the base edge 10, extend in the same general direction as the adjacent edges 11 and 12, respectively. Also, the edges 22 and 32 are nearer edges 11 and 12, respectively, than the edges 21 and 31, which are inclined at the lesser angle to the base edge 10. In addition, the edges 21 and 31, and 21' and 31', extend in the opposite general directions to the adjacent exterior edges 11

and 12, and 11' and 12', respectively. This relationship between the interior edges, and also between the interior edges and the adjacent exterior edges is of importance during use of the device, as explained hereinafter.

The device D' is provided with an aperture 20' providing interior edges 21', 22' and 23' adjacent exterior edge 11', and similar in inclination to base edge 10 and in general direction to the interior edges of aperture 20 of device D. Device D' is also provided with an aperture 30' adjacent exterior edge 12' and providing interior edges 31', 32' and 33' similar to the edges of aperture 30 of device D, as will be evident.

Device D is further provided with a central aperture 40 which provides side edges 41 disposed at an angle of 90° to base edge 10, and are used for the same purpose as exterior edges 13 of device D', as will appear hereinafter. Aperture 40 may be completed by a lower edge 42, parallel to base edge 10, and upper edges 43, parallel to the adjacent exterior edges 11 and 12, respectively.

The devices D and D' may be made of any suitable material, such as celluloid, or a resinous material, either thermo-plastic, such as polystyrene, vinyl acetate, vinyl chloride-acetate copolymer, or thermal setting, such as of the phenolic or urea types. The devices may be transparent or translucent, if desired, or opaque, depending upon the material and method of manufacture. Also, the devices may be cast, or molded, or machined from extruded parts or rolled or cast sheets. The devices may be colored, if desired, or made from metal or wood, and also may be made in any desired size or sizes. The only requirement is that the devices be sufficiently strong to withstand usage, and preferably of such construction or material as to have little tendency to twist or warp. Thus, a laminated construction is also possible.

In making drawings with a device of this invention, the base edge 10 is placed against a T-square or similar straight edge, and the exterior edges 11 and 12 of device D, and 11' and 12' of device D' are utilized in drawing two of the three principal axes of the object, at angles of 36° 52' 11.63" to the horizontal or base line, while edge 13 of device D' and interior edges 41 of device D are utilized in drawing the third axis and lines parallel thereto, at an angle of 90° to the horizontal or base line. For accuracy, dimensions along the inclined axes are made to full scale, while dimensions along the vertical or 90° axis are made to a 3/4 scale. The result is an optically balanced three dimensional dimetric system of drawing having receding axes at equiangular position with respect to horizontal or vertical reference. A perspective drawing is not mathematically correct, nor can it be made so; an isometric drawing, whose axes are 120° apart, is not optically balanced; and a cabinet drawing, one axis of which recedes at an angle of 45° but dimensions along which are drawn to a scale of 1/2, is neither geometrically correct nor mathematically accurate. Devices constructed in accordance with this invention have been used widely to make dimetric drawings for industrial purposes, which are particularly effective in "exploded" views, wherein the various parts of an apparatus are shown in separated relation but in relative positions similar to those assumed when the apparatus is assembled.

A further important use of the devices of this

invention lie in making piping diagrams and the like, such as in Fig. 3. Since the piping of an office building, apartment house, or the like, is often quite complicated, and usually involves 5 risers, or vertical runs, horizontal runs in both directions, and long and short lengths of pipe which extend at an angle of 45° to the horizontal directions, any tool which will permit a complete piping diagram to be made with ease is extremely valuable, particularly when the diagram is easily understood. The device of this invention is such a tool.

As in Fig. 3, the piping system is supplied with steam or hot water by a furnace F. The vertical runs or risers 113 are drawn with the edges 13 or 41 of the devices of this invention; the horizontal pipes or runs 111 in one direction are drawn with the edges 11 or 11'; the horizontal pipes or runs 112 in the perpendicular direction are drawn with the edges 12 or 12'; the 45° riser pipes or runs 121 and 122, extending upwardly to the left and right, respectively, at right angles to pipes 112 but in vertical planes parallel to the vertical plane of horizontal pipes 111, are drawn with edges 21 or 21' and 22 or 22', respectively; and the pipes or runs 131 and 132 extending at 45° upwardly at right angles to pipes 111 but in vertical planes parallel to the vertical plane of horizontal pipes 112 to the right and left, respectively, are drawn with edges 31 or 31', and 32 or 32', respectively. Such piping comprises all the usual directions which piping may take, the conventional fittings being unions for continuations of straight runs, 90° L's or T's for take-off of a pipe in a perpendicular direction and 45° L's or T's for take-off of a pipe in a 45° direction.

From the above, several results of value are evident. For instance, the adjacency of edges 21 and 22 to edge 11, and of edges 21' and 22' to edge 11', as well as the adjacency of edges 31 and 32 to edge 12, and of edges 31' and 32' to edge 12', facilitates selection of the proper edge to draw a 45° riser, and reduces mistakes in use, as well as difficulties in teaching and/or learning use of the device. In addition, the preferred relation between edges 21 and 22, 31 and 32, 21' and 22', and 31' and 32', simplify the task of identifying the proper direction for the 45° riser to take, since edges with which lines slope upwardly to the left are drawn slope upwardly to the left themselves in an unmistakable manner, and similarly for the edges which slope upwardly to the right. Also, the presence of edges parallel to the edges representative of the principal axes is a constant reminder of the vertical plane in which the 45° risers to be drawn are correctly placed. Thus, there is a definite and valuable cooperation, not only between the edges 11 and 12 and lower edges of the apertures, for instance, but also between the edges 11 and 12 and the position of the apertures or additional edges for drawing 45° risers or the like.

The device D' of Fig. 2 possesses certain advantages not possessed by the device D. The relative position of edges 11' and 12' is the more usual relationship between the horizontal axes, i. e., the object or the like is more often represented as being looked down upon rather than looked up at. Furthermore, less shifting of the device D', in making a usual drawing, is necessary. Also, in shifting from one horizontal axis to the other, the drawing is obscured less during such movement. The sides 13 are also more convenient to use in drawing vertical lines.

From the foregoing, it will be apparent that a geometrical instrument of this invention fulfills to a marked degree the objects and requirements hereinbefore set forth. The numerous novel features thereof, including the combination of the inclined exterior edges and the interior edges provided by the apertures, assist materially in increasing accuracy and ease of use, and also simplify the problems involved in making accurate drawings with readiness and certainty.

It will be understood that various changes may be made, since the useful edges may all be exterior edges, or all interior edges, or any combination of the same. Although two different embodiments have been illustrated and described, it will be understood that other embodiments may exist and that changes other than those indicated may be made without departing from the spirit and scope of this invention.

What is claimed is:

1. A geometrical instrument having a plurality of co-planar edges, including an exterior base edge; a first and second inclined exterior edge extending in opposite general directions and each inclined at an angle of $36^{\circ} 52' 11.63''$ to said base edge; a first and second interior edge provided by an aperture adjacent said first inclined exterior edge, said first interior edge being inclined at an angle of $59^{\circ} 21'$ to said base edge and extending in the same general direction as said first inclined exterior edge, and said second interior edge being inclined at an angle of $10^{\circ} 37' 10''$ to said base edge, being more closely adjacent said base edge than said first interior edge, and extending in a general direction opposite to said first inclined exterior edge; and a third and fourth interior edge provided by an aperture adjacent said second inclined exterior edge, said third interior edge being inclined at an angle of $59^{\circ} 21'$ to said base edge and extending the same general direction as said second inclined exterior edge, and said fourth interior edge being inclined at an angle of $10^{\circ} 37' 10''$ to said base edge, being spaced more closely adjacent said base edge than said third interior edge, and extending in a general direction opposite to said second inclined exterior edge.

2. A geometrical instrument as defined in claim 1, wherein said inclined exterior edges intersect at their upper ends.

3. A geometrical instrument as defined in claim 1, wherein said inclined exterior edges intersect at the top, and said device includes a central aperture providing at least one interior edge disposed at 90° to said base edge.

4. A geometrical instrument as defined in claim 1, wherein said apertures are triangular in shape and the third edge thereof is parallel to the adjacent inclined exterior edge.

5. A geometrical instrument having a plurality of co-planar exterior and interior edges, said interior edges being provided by apertures in said device, said edges including an exterior base edge; a second exterior edge inclined at an angle of $36^{\circ} 52' 11.63''$ to said base edge; a third exterior edge also inclined at an angle of $36^{\circ} 52' 11.63''$ to said base edge but extending in the opposite general direction to said second exterior edge and intersecting the same at an upper point; interior edges provided by an aperture adjacent said second exterior edge and including an interior edge parallel to said second

exterior edge, an interior edge extending in the same general direction as said second exterior edge and at an angle of $59^{\circ} 21'$ to said base edge, and an interior edge extending in the opposite general direction from said second exterior edge and at an angle of $10^{\circ} 37' 10''$ to said base edge; interior edges provided by an aperture adjacent said third exterior edge, and including an interior edge parallel to said third exterior edge, an interior edge extending in the same general direction as said third exterior edge and at an angle of $59^{\circ} 21'$ to said third exterior edge, and an interior edge extending in the opposite general direction from said third exterior edge and at an angle of $10^{\circ} 37' 10''$ to said base edge; and interior edges provided by a central aperture and including parallel side edges of said aperture extending at 90° to said base edge, a lower edge parallel to said base edge, and intersecting upper edges parallel to said second and third exterior edges.

6. A geometrical instrument having a plurality of co-planar exterior and interior edges, said interior edges being provided by apertures in said device, said edges including an exterior base edge; exterior side edges extending at 90° to said base edge; an inclined exterior edge extending downwardly and inwardly from an upper point of intersection with one of said side edges and at an angle of $36^{\circ} 52' 11.63''$ to said base edge; another inclined exterior edge extending downwardly and inwardly from an upper point of intersection with the other side edge and at an angle of $36^{\circ} 52' 11.63''$ to said base edge and to a point of intersection with the other inclined exterior edge; and interior edges provided by a triangular aperture adjacent each said inclined exterior edge, one edge of each aperture being parallel to said inclined exterior edge, another and lowermost edge of each aperture extending in an opposite general direction from said parallel edge and at an angle of $10^{\circ} 37' 10''$ to said base edge, and the third edge of each aperture extending in the same general direction as said parallel edge and at an angle of $59^{\circ} 21'$ to said base edge.
